Des. 196,583
Patented Oct. 15, 1963

196,583

VOICE DEVELOPING DEVICE

Ernest Camerino, 91 Surf Road, Lindenhurst, N.Y.

Filed Nov. 27, 1962, Ser. No. 72,617

Term of patent 7 years

(Cl. D25—1)

FIG. 1 is a top plan view of a voice developing device, showing my new design;

FIG. 2 is a side elevational view thereof, the opposite side being the same;

FIG. 3 is a bottom plan view thereof;

FIG. 3 is a bottom plan view thereof;

FIG. 4 is a view of the left end of FIG. 1; and

FIG. 5 is a view of the right end of FIG. 1.

I claim:

The ornamental design for a voice developing device, as shown.
